UNITED STATES PATENT OFFICE.

JOHN SQUIRES, OF GROSSE POINT PARK, MICHIGAN, AND CALVIN P. KING, OF CHICAGO, ILLINOIS.

LIQUID-FUEL IGNITER AND BURNER.

1,307,797.

Specification of Letters Patent. Patented June 24, 1919.

Application filed December 17, 1918. Serial No. 267,125.

To all whom it may concern:

Be it known that we, JOHN SQUIRES and CALVIN P. KING, citizens of the United States, and residing at Grosse Point Park, 5 county of Wayne, and State of Michigan, and Chicago, county of Cook, and State of Illinois, respectively, have invented a new and Improved Liquid-Fuel Igniter and Burner, of which the following is a specification.

This invention relates to means for igniting liquid fuels, and its object is to provide a combination of a vaporizing device, and an atomizer which will be made operative by 15 the closing of a switch in an electrical circuit, with or without the use of a separate igniter, which device shall be simple in construction and which may be easily and readily combined from well known elements.

20 This invention consists in the combination of a source of atomized fuel, preferably a fan driven by an electric motor, which fan is attached to a carburetor, of a heating element, preferably a trough made of a strip of 25 high resistance metal which becomes highly heated when in a proper electric circuit and positioned to receive such drops of the fuel as may fall from the atomizer. It also consists in combination with the atomizer and 30 vaporizer of a spark plug adjacent the vaporizer so that a spark may ignite the fuel vapors which rise from the heating element. It further consists in connecting the heating element and the motor in series, connecting the primary circuit of the induction coil for the spark plug in parallel with the circuit of the motor and heating element, and connecting a switch into a main from 35 which the parallel circuits derive their current.

In the accompanying drawing, Figure 1 is a central vertical section of this igniter and burner. Fig. 2 is a diagram showing the electric circuits. Fig. 3 is a section of 45 the vaporizer on a larger scale. Fig. 4 is a section of a portion of the carburetor. Fig. 5 is a cross section of the vaporizer.

Similar reference characters indicate like parts throughout the several views. 50 The combustion chamber 1 may be of any shape or size and may be designed for any purpose. The carburetor 2 is of any desired type adapted for liquid fuel. Instead of drawing air through the mixing tube 3, a 55 fan 4 is designed to force the air through

this tube and the same effect is obtained. The fuel flows through the passage 5 from a float chamber 6 and through openings 7 into the Venturi tube 8.

The fan is driven by an electric motor 9 shown conventionally in Fig. 2, and fuel will collect at the discharge end of the nozzle 10 and drip down from the lowest point thereof, such as a lip 11, onto the heating element 12 which is preferably a ribbon of 65 high resistance metal bent upon itself and creased to constitute a trough, the loop 13 at the outer end providing for the unequal expansions. Because of the cold liquid fuel continuing to drip down onto the vaporizer 70 this element will be prevented from over-heating from the temperature of the furnace. The bolt 14 constitutes one terminal of this element while the sleeve 15 constitutes the other. Nuts 16 and 17 complete 75 the vaporizer.

The spark plug 18 is of any desired construction and may be connected to the secondary winding 19 of an induction coil and grounded in any desired manner. 80

The wiring for this igniter is simple and is indicated in Fig. 2. A switch 21 is connected into a main wire 22 and a current source 23 in the other main wire 24. The primary winding 25 of the induction coil 85 connects to the two main wires and may be provided with a vibrator 26. The current which passes through the motor 9 may also pass through the vaporizer 12, the wires 27 and 28 completing a circuit which is parallel to the circuit of the primary winding 90 of the induction coil.

When the switch is closed, the fan will force air through the carburetor and atomized fuel will be thrown into the combustion chamber. At the same time, the trough 12 will become highly heated and the fuel that drips from the lip 11 on the nozzle 10 onto this heating element will be vaporized and this vapor, mixed with the air of the combustion chamber, will ignite which will cause the vapor blown from the nozzle 10 to ignite. The spark plug shown in the drawing may be omitted where the proportions, current, and resistances are such that 100 the temperature of the vaporizer becomes sufficient to ignite the vaporized fuel. 105

It will be understood that the types of atomizer, vaporizer or spark plug form no part of the present invention and that any 110

desired constructions of these elements and circuits between them may be adopted so long as the vaporizer is found to receive and hold the drops of liquid which fall 5 from the nozzle 10 until this fuel evaporates. The sizes and proportions of the various parts may therefore all be changed by those skilled in the art without departing from the spirit of our invention as set 10 forth in the following claims, and any other means for producing the air currents and feeding the fuel may be employed.

We claim:

1. An igniter and burner for liquid fuel 15 comprising an atomizer and a heating device positioned to receive liquid fuel from the atomizer and to vaporize it independently of the heat generated by the burning of the fuel.
2. An igniter and burner for liquid fuel 20 comprising an electrically operated atomizer and a vaporizer comprising an electrical heating element positioned to receive liquid fuel from the atomizer.
3. An igniter and burner for liquid fuel 25 comprising an atomizer, a heating device positioned to receive liquid fuel from the atomizer to vaporize the fuel independently of the heat generated by the burning of the fuel, a spark plug positioned adjacent the vaporizer to ignite the fuel vapor, and a combustion chamber to receive the discharge of the atomizer.
4. An igniter and burner for liquid fuel 35 comprising a carburetor, a fan to force air through the carburetor, an electric motor to drive the fan, an electrically heated vaporizer adapted to receive drops of liquid fuel from the discharge nozzle of the carburetor, a current source, and a circuit between the current source, motor and vaporizer.
5. An igniter and burner for liquid fuel

comprising a carburetor, a fan to force air 45 through the carburetor, an electric motor to drive the fan, an electrically heated vaporizer adapted to receive drops of liquid fuel from the discharge nozzle of the carburetor, a current source, a circuit between the current source, motor and vaporizer, and 50 an igniter adjacent the vaporizer.

6. In an igniter and burner for liquid fuel, the combination of a carburetor, an air passage leading therefrom, a fan for forcing air through said passage, an electric 55 motor to drive the fan, an electrically heated vaporizer positioned below the discharge end of said passage and adapted to receive liquid fuel therefrom, a current source, an electric circuit connecting the 60 current source, motor and vaporizer, a spark plug mounted adjacent the vaporizer, and an electric circuit between the spark plug and current source parallel to the first named circuit.

7. An igniter and burner for liquid fuel comprising an atomizer, an electric motor for operating the atomizer, an electrically heated vaporizer positioned to receive liquid fuel from the atomizer, and a spark 70 plug positioned adjacent the vaporizer to ignite the fuel vapor.

8. An igniter and burner for liquid fuel comprising an atomizer, an electric motor for operating the atomizer, an electrically 75 heated vaporizer positioned to receive fuel from the atomizer, a spark plug positioned adjacent the vaporizer to ignite the fuel, a current source, electric circuits between the current source, motor and vaporizer 80 and between the current source and spark plug, and a switch for controlling said circuits.

JOHN SQUIRES.
CALVIN P. KING.
